WILHELM B. BRONANDER, OF MONTCLAIR, NEW JERSEY, ASSIGNOR TO AMERICAN MACHINE & FOUNDRY COMPANY, A CORPORATION OF NEW JERSEY.

CIGARETTE-MACHINE CUT-OFF.

Application filed August 13, 1926. Serial No. 128,985.

This invention relates to a cigarette machine cutoff, and has for its main object the production of a device of this kind in which the angular velocity of the knife is accelerated during cutting action only in order to produce faster and better cuts in the cigarette rod. A further object is the provision of means for producing harmonious reciprocations of the knife along the cigarette rod regardless of its varying angular velocity. With these and other objects not specifically mentioned in view, the invention consists in certain constructions and combinations which will be hereinafter fully described and then specifically set forth in the claims hereunto appended.

In the accompanying drawings, in which like characters of reference indicate the same or like parts, Figs. 1 and 2 are respectively plan and side elevations, partly broken away, of a cutoff constructed in accordance with the invention; and Fig. 3 is an elevation taken on the line 3—3 in Fig. 2.

In carrying the invention into effect, there is provided a knife, a holder for the knife, an elongated spiral gear carrying and rotat- 25 ing said holder, a spiral pinion rotating said gear, and means for reciprocating said gear, holder and knife to produce acceleration of the angular velocity of the same during cutting action only. In the best constructions contemplated, said means produces harmonious reciprocations of the gear, holder and knife regardless of their varying angular 30 velocity. The above mentioned parts may be varied in construction within the scope of the claims, for the specific structure selected to illustrate the invention is but one of numerous possible concrete embodiments of 35 the same. The invention therefore is not to be restricted to the precise details of the structure shown and described.

Referring to the drawings, the device is mounted on a base 4 of a cigarette machine in connection with which it is used, the elongated spiral gear 5 being supported by uprights 6 and 7, and the shaft 8 of a spiral pinion 9 by the bearing column 10. The gear 5 is mounted on a shaft 11 which also carries disks 12 and 13, forming a knife holder and between which a knife blade 14 is clamped by means of a nut 15.

The shaft 8, which is rotated by suitable

means from the main drive of the cigarette machine not shown, carries a crank 16 associated with the pinion 9. The crank pin 17 of the crank 16, by means of a connecting rod 18, is joined to a lever 19 fulcrumed on a stud 20, supported by a column 21, carried by a bracket 22, secured to the base 4. At 55 the point where it crosses the shaft 11, the lever 19 carries a roller 23 working in an annular groove 24 formed between a collar 25 on the gear 5 and the hub face of the disk 12. 65

A second roller 26 also works in the lower part of the groove 24. This roller is attached to a slide 27, to which is fastened a holder 28 carrying a ledger plate 29 co-acting with the knife 14, a cigarette tube 30, and a bell mouth 31, through which the cigarette rod, marked 32, passes in the usual manner while being cut by the knife 14. The slide 27, which is thus caused to have a harmonious reciprocating movement conforming 70 with that of the gear 5, holders 12—13 and knife 14, is supported by a guide 33, attached to the base 4, in which it is held by gibs 34 placed upon either side of the guide 33. 75

The gear 5, knife holder 12—13 and knife 14 are rotated by the engagement of the pinion 9 with the gear 5. They are also given a harmonious reciprocating movement by means of the crank 16 and operating connections. The simultaneous rotary and reciprocating motion of the gear 5 causes an acceleration of angular velocity of the gear, the knife holder and the knife during that portion of the cycle in which the direction 85 of the longitudinal movement of the gear is opposed to that of the rotation of the pinion 9, and a retardation of angular velocity during that portion of the cycle in which the two directions coincide. The di- 90

rection of rotation and the relative arrangement of the parts are therefore so chosen that the angular velocity of the knife while cutting corresponds with the accelerated motion, and its angular velocity while running idle corresponds with the retarded motion, so that, from a uniform angular velocity of the pinion 9, a much greater cutting speed can be attained than by the driving means formerly employed, yet the reciprocations of 100 the gear, the knife holder and the knife, 105

being controlled by the crank 16, are harmonious regardless of the angular velocity of the same parts.

What is claimed is:

- 5 1. In a cigarette machine cutoff, the combination with a knife, of a holder for said knife, an elongated spiral gear carrying and rotating said holder, a spiral pinion rotating said gear, and means for reciprocating said gear, holder and knife to produce acceleration of the angular velocity of the same during cutting action only.
- 10 2. In a cigarette machine cutoff, the combination with a knife, of a holder for said knife, an elongated spiral gear carrying and rotating said holder, a spiral pinion rotating said gear, and means for reciprocating said gear, holder and knife to produce acceleration of the angular velocity of the same during cutting action only.
- 15 3. In a cigarette machine cutoff, the combination with a knife, of a holder for said knife, an elongated spiral gear carrying and rotating said holder, a spiral pinion rotating said gear, and means for reciprocating said gear, holder and knife to produce acceleration of the angular velocity of the same during cutting action only, said means producing harmonious reciprocations of said gear, holder and knife regardless of their varying angular velocity.
- 20 4. In a cigarette machine cutoff, the combination with a knife, of a holder for said knife, an elongated spiral gear carrying and rotating said holder, a spiral pinion rotating said gear, and means for reciprocating said gear, holder and knife to produce acceleration of the angular velocity of the same during cutting action only, said means including a crank associated with said pinion, a connecting rod actuated by said crank, and a lever actuated by said rod and engaging said holder.
- 25 5. In a cigarette machine cutoff, the combination with a knife, of a holder for said knife, an elongated spiral gear carrying and rotating said holder, a spiral pinion rotating said gear, means for reciprocating said gear, holder and knife to produce acceleration of the angular velocity of the same during cutting action only, and a ledger plate coacting with said knife, said means producing harmonious reciprocations of said gear, holder, knife and ledger plate regardless of the varying angular velocity of said gear, holder and knife.
- 30

same during cutting action only, said means being crank-actuated.

4. In a cigarette machine cutoff, the combination with a knife, of a holder for said knife, an elongated spiral gear carrying and rotating said holder, a spiral pinion rotating said gear, and means for reciprocating said gear, holder and knife to produce acceleration of the angular velocity of the same during cutting action only, said means including a crank associated with said pinion, a connecting rod actuated by said crank, and a lever actuated by said rod and engaging said holder.

5. In a cigarette machine cutoff, the combination with a knife, of a holder for said knife, an elongated spiral gear carrying and rotating said holder, a spiral pinion rotating said gear, means for reciprocating said gear, holder and knife to produce acceleration of the angular velocity of the same during cutting action only, and a ledger plate coacting with said knife, said means producing harmonious reciprocations of said gear, holder, knife and ledger plate regardless of the varying angular velocity of said gear, holder and knife.

In testimony whereof, I have signed my name to this specification.

WILHELM B. BRONANDER.
